UNITED STATES PATENT OFFICE.

JAMES E. MEGINN, OF COVINA, CALIFORNIA.

DESIGN FOR A SHOE-HORN.

45,014.

Specification for Design.

Patented Dec. 9, 1913.

Application filed September 22, 1913. Serial No. 791,235. Term of patent 7 years.

To all whom it may concern:

Be it known that I, JAMES E. MEGINN, a citizen of the United States, residing at Covina, in the county of Los Angeles and State of California, have invented a new, original, and ornamental Design for Shoe-Horns, of which the following is a specification, reference being had to the accompanying drawing, forming part thereof.

In the drawings: Figure 1 is a front eleva-

tion of the shoe horn of my invention. Fig. 2 is a side view in elevation, and Fig. 3 is a rear view of the shoe horn.

I claim—

The ornamental design for a shoe horn, as shown.

JAMES E. MEGINN.
